UNITED STATES PATENT OFFICE.

ALBERT J. BROWN, OF SANDUSKY, OHIO.

TAPPET-ADJUSTING TOOL.

Application filed May 3, 1926. Serial No. 106,311.

The present invention relates to a valve tappet adjusting tool, and has for its object to provide a device of this character which embodies novel features of construction, 5 whereby the tappets of valve in head motors can be quickly and accurately adjusted.

Further objects of the invention are to provide a tool of this character which can be easily and quickly applied to the adjusting screws and manipulated to loosen and turn the same the required amount, which enables the proper clearance to be accurately obtained, which will facilitate the obtaining 10 of a uniform adjustment of all of the tappets 15 on a motor, and which has a compact and convenient arrangement of parts.

While one particular embodiment of the invention is shown and described for illustrative purposes, it will be understood that 20 many modifications and changes can be made in the particular proportions and minor details of construction without departing from the spirit of the invention.

For a full understanding of the invention reference is to be had to the following 25 description and accompanying drawings, in which

Figure 1 is a longitudinal sectional view 30 through a valve tappet adjusting tool which is constructed in accordance with the invention, showing the same as operatively applied to a rocker arm.

Figure 2 is a side elevation of the upper 35 end of the tool.

Figure 3 is a horizontal sectional view 40 on the line 3—3 of Figure 1.

Corresponding and like parts are referred 45 to in the following description and indicated on all of the views of the drawing 50 by like reference characters.

Referring to the drawings, the numeral 1 55 designates a conventional rocker arm which is pivotally mounted at a point between its ends on a rocker arm shaft 2 which extends longitudinally of the motor (not shown) and is of the usual and well known construction. One end of the rocker arm is adapted to engage the valve stem 3, while the other end of the rocker arm is provided with an adjusting screw 4 which is threaded therein and which is arranged for engagement by the usual push rod 5. The upper end of the adjusting screw 4 is provided with the usual kerf to receive the bit of a screwdriver, and a jam nut 6 which is threaded upon the adjusting screw is adapted to be turned tightly

against the upper surface of the rocker arm to lock the screw in an adjusted position. This is the conventional form of rocker arm for use in connection with valve in head motors and no claim to novelty is based 60 thereon.

The tool includes a sleeve 7 which is formed at one end thereof with a polygonal socket portion 8 adapted to fit over and engage the jam nut 6. Handle members 9 project laterally from opposite sides of the sleeve and provide a means for forcibly rotating the same to loosen or tighten the jam nut as may be desired. The inner ends of 65 the handle members extend through openings in opposite sides of the sleeve and are threaded in a collar 10 which is arranged within the sleeve.

Extending through the sleeve and projecting 70 from the end thereof which is remote from the socket 8 is a stem 11. The end of the stem within the sleeve is formed with a bit portion 12 which is adapted to engage the kerf at the end of the adjusting screw 4, while the end of the stem which projects from the sleeve has a knurled finger piece 13 applied thereto. A coil spring 14 is arranged within the sleeve and surrounds the 75 stem, said spring being interposed between the collar 10 and a shoulder or transverse pin 15 on the stem, so that the spring normally tends to slide the stem longitudinally through the sleeve and force the bit 12 into engagement with the adjusting screw. 80

A head 16 is rotatably mounted on the projecting end of the stem 11, said head being formed with a skirt portion 16^a which extends over the sleeve 7, and having the opposite end thereof suitably recessed to receive an adjusting collar 17 which is also rotatably mounted upon the stem. The head 16 is provided with a suitable detent such as the ball 18 which is adapted to yieldably engage a depression or seat 19 in one side of 95 the stem. The ball is shown as engaged by a spring 20 which is held in position by means of a screw 21. In a similar manner the adjusting collar 17 is provided with a spring detent such as the ball 22 which is 100 adapted to engage a seat 23 formed in one side of the stem 11. The two seats 19 and 23 are arranged in longitudinal alignment on the stem, being suitably spaced for engagement with the respective spring detents. 105 The ball 22 is shown as engaged by a spring 24, the outer end of which has a sliding en-

gagement with an adjusting ring 25 which is rotatably mounted on the head 16, the end of the head being suitably rabbetted to receive the ring. A screw 26 extends through the adjusting ring 25 and engages the adjusting collar 17, said screw passing through a slot 27 which is formed in the head 16. The projecting end of the screw forms a finger piece by means of which the ring can 10 be rotated.

In the use of the tool the socket 8 at the end of the sleeve 7 is applied to the jam nut 6, and the latter loosened by rotating the sleeve. The bit 12 at the lower end of the stem 11 is 15 brought into engagement with the adjusting screw by the action of the spring 14, and the operator then grasps the knurled finger piece 13 and rotates the stem until the end of the rocker arm is brought into a firm engagement 20 with the valve stem. It is then desired to slightly loosen the screw in order to provide a certain definite but slight clearance between the valves stem and the rocker arm, this clearance being usually somewhere 25 between .004 of an inch and .008 of an inch. It is necessary that this adjustment be made with accuracy and that the adjustment on all of the valves of the motor be uniform, and the present tool provides a means for obtaining 30 the proper adjustment with precision. When the adjusting screw is tightened to bring the rocker arm into a firm engagement with the valve stem, the head 16 is positioned on the stem with the ball detent 18 thereof 35 in engagement with the seat 19. The adjusting collar 17 has been previously rotated a predetermined amount so that the ball detent 22 thereof has been moved out of engagement with the seat 23. The exact 40 amount of this rotation of the adjusting collar 17 is determined by the amount of clearance which is desired between the rocker arm and valve stem. After the adjusting screw has been turned to take up all looseness, the operator holds the head 16 and adjusting 45 ring 25 firmly with one hand, while he turns the stem 11 in a direction to loosen the adjusting screw until the ball detent 22 of the adjusting sleeve snaps into the seat 23. The necessary clearance has then been 50 obtained, and the jam nut can be tightened.

In order to facilitate the proper setting of the adjusting ring 25, the said ring is provided with a pointer 28 which moves over 55 graduations 29 on the head. When it is desired to obtain a certain adjustment the adjusting ring 25 is turned a predetermined amount as determined by the movement of the pointer 28 along the graduations 29. This 60 adjustment of the ring determines the amount of backward rotation which must be given to the adjusting screw before the ball detent 22 of the adjusting collar snaps into the seat 23 of the stem. The device can be 65 set to give a smaller or greater clearance, as

may be desired, and by using the same adjustment for all of the valve tappets on the motor they will all be left with exactly the same clearance. The tool has a compact arrangement, and can be easily carried in the hand and quickly placed in operative position. 70

If desired, a coil spring 30 may be arranged in the upper end of the sleeve 7, and one end of the spring connected to the head 16, while the other end is connected to the sleeve. This spring will operate to return the head to zero position with the ball 75 seated in the recess 19 after each operation of the device. 80

Having thus described my invention what I claim as new and desire to secure by Letters Patent is,

1. A valve tappet adjusting tool, including a socket member adapted to engage the jam nut, means for rotating the socket member to turn the jam nut, a stem rotatable within the socket and having a bit at the end thereof adapted to engage the adjusting screw, and means associated with the stem 85 for enabling a preselected amount of backward rotation to be imparted thereto to obtain a predetermined clearance in the valve mechanism. 90

2. A valve tappet adjusting tool, including a socket member adapted to engage the jam nut, means for rotating the socket member to turn the jam nut, a stem rotatable within the socket member and formed with a bit adapted to engage the adjusting screw, and detent means associated with the stem 100 for enabling a preselected amount of backward rotation to be imparted thereto independently of the socket member to obtain the desired clearance in the valve mechanism. 105

3. A valve tappet adjusting tool including a socket member adapted to engage the jam nut, a stem rotatable within the socket member and formed with a bit adapted to engage the adjusting screw, a head on the stem, 110 an adjusting sleeve rotatable on the stem, cooperating detent elements on the stem and sleeve, and means for setting the detent element of the sleeve at a predetermined position in the path of the detent member on the stem, whereby the detent members will engage each other when the stem has been turned backward a predetermined amount to obtain the desired clearance in the valve mechanism. 115

4. A valve tappet adjusting tool, including a socket member adapted to engage the jam nut, a stem rotatable within the socket member and formed with a bit adapted to engage the adjusting screw, a head rotatable on the 125 stem, means for holding the stem in a certain position with respect to the head, an adjusting sleeve mounted on the stem, cooperating detent elements on the stem and sleeve, and means for setting the sleeve with the detent 130

element thereof at a predetermined position in the path of the detent element of the stem, whereby the detent elements will engage each other when the stem has been turned backward a sufficient amount to obtain the desired clearance in the valve mechanism.

5. A valve tappet adjusting tool, including a socket member adapted to engage the jam nut, a stem rotatable within the socket member and formed with a bit adapted to engage the adjusting screw, a head rotatable on the stem, detent means for holding the head at a certain position on the stem, an adjusting sleeve rotatable on the stem, cooperating detent elements on the stem and adjusting sleeve, the detent element on the stem having a fixed relation with respect to the detent means of the head, and means for setting the sleeve with the detent element thereof held in 20 a predetermined position in the path of the detent element of the stem, whereby the detent elements will engage each other when the stem has been rotated a sufficient amount to obtain the desired clearance in the valve mechanism.

6. A valve tappet adjusting tool including a socket member adapted to engage the jam nut, a stem rotatable within the socket member and formed with a bit adapted to engage the adjusting screw, a head rotatable on the stem, means for holding the head in a certain position on the stem, an adjusting sleeve rotatable on the stem, a ring rotatably mounted on the head and operatively connected 35 with the sleeve, cooperating detent elements on the sleeve and stem, respectively, and means associated with the ring for rotating the sleeve to set the detent element thereof at a predetermined position in the path of the detent element of the sleeve, whereby the two detent elements will engage each other when the stem has been rotated a sufficient amount to obtain the desired clearance in the valve mechanism.

45. 7. A valve tappet adjusting tool, including a socket member adapted to engage the jam nut, a stem rotatably mounted within the socket member and formed with a bit adapted to engage the adjusting screw, a head 50 mounted on the stem, means for holding the head at a certain position thereon, an adjusting sleeve rotatable on the stem, the head

having one end thereof recessed to receive the sleeve and the said end of the head having a slot therein, a ring rotatable on the head, 55 a fastening member connecting the ring to the sleeve and operating within the slot, cooperating detent elements on the stem and sleeve, respectively, and means associated with the ring for turning the sleeve to set 60 the detent element thereof in a predetermined position in the path of the detent element of the sleeve, whereby the two detent elements will engage each other when the stem has been rotated a sufficient amount 65 to obtain the desired clearance in the valve mechanism.

8. A valve tappet adjusting tool, including a stem provided with means for engaging the adjusting screw, an adjusting sleeve rotatable on the stem, cooperating detent elements on the stem and sleeve, respectively, and means for selectively presetting the sleeve with the detent element thereof in a predetermined position in the path of the detent element of the stem and in advance thereof 70 whereby the two detent elements will engage each other when the stem has been rotated a predetermined amount.

9. A valve tappet adjusting tool including 80 a stem provided with means for engaging an adjusting screw, detent means for checking the rotation of the stem, and means for selectively presetting the detent means to become operative upon a predetermined rotation of the stem.

10. A valve tappet adjusting tool including a socket member adapted to engage the jam nut, means for rotating the socket member to turn the jam nut, a stem rotatable 90 within the socket and having a bit at the end thereof adapted to engage the adjusting screw, a yieldable connection between the stem and the socket member for yieldably holding the stem in a certain position relative to the socket member, and means for enabling a preselected amount of rotation to be imparted to the stem from the said position independently of the socket member to obtain a predetermined clearance in the valve 95 mechanism.

In testimony whereof, I affix my signature.

ALBERT J. BROWN.
